UNITED STATES PATENT OFFICE.

JACOB A. MOLLER, JR., OF NEW YORK, N. Y.

DESIGN FOR A BOX.

SPECIFICATION forming part of Design No. 30,171, dated February 14, 1899.

Application filed January 20, 1899. Serial No. 702,852. Term of patent 7 years.

To all whom it may concern:

Be it known that I, JACOB A. MOLLER, Jr., a citizen of the United States, residing at the city of New York, borough of Manhattan, in 5 the county and State of New York, have invented and produced a new and original Design for a Box, of which the following is a specification, reference being had to the accompanying drawings, forming a part thereof, 10 in which—

Figure 1 is a view of the obverse side of a box, illustrating my design; and Fig. 2 is a view of the reverse side.

The leading features of the design consist 15 in a decoration for one side of the box, repre-

senting a human figure in an attitude of attention or surprise and a decoration for the opposite side of the box, representing a sea-craft of the Norseman period.

The minor features of the design consist of 20 garlands of vines located at each side of the human figure and of a cover ornamented with leaf-like scrolls and dragon-like subjects.

I claim—

The design for a box herein shown and de- 25 scribed.

JACOB A. MOLLER, JR.
